UNITED STATES PATENT OFFICE.

ABRAHAM W. ROSEN, OF NEW YORK, N. Y.

DESIGN FOR A COMBINED ASH RECEIVER AND MATCH BOX.

Application filed March 3, 1927. Serial No. 20,956. Term of patent 3½ years.

To all whom it may concern:

Be it known that I, ABRAHAM W. ROSEN, a citizen of the United States, and a resident of the city of New York, borough of Manhattan, in the county and State of New York, United States of America, have invented a new, original, and ornamental Design for Combined Ash Receiver and Match Box, of which the following is a specification, reference being had to the accompanying drawing, forming part thereof.

Fig. 1 is a view in front elevation of a combined ash receiver and match box showing my new design.

Fig. 2 is a top plan view thereof.

Fig. 3 is a view in side elevation thereof, the dotted lines in Figs. 2 and 3 indicating an attaching bracket.

I claim:

The ornamental design for a combined ash receiver and match box substantially as shown and described.

ABRAHAM W. ROSEN.
